UNITED STATES PATENT OFFICE.

LEVI T. PECK, OF HONOLULU, TERRITORY OF HAWAII.

TRANSFER-TICKET.

No. 856,904.

Specification of Letters Patent.

Patented June 11, 1907.

Application filed November 22, 1905. Serial No. 288,602.

To all whom it may concern:

Be it known that I, Levi T. Peck, a citizen of the United States, residing at Honolulu, Hawaii, have invented certain new and useful Improvements in Transfer-Tickets, of which the following is a description, reference being had to the accompanying drawing and to the letters and figures of reference marked thereon.

10 This invention relates to transfers for use on street car lines, and has for its principal object to prevent riding for an unlimited period for payment of a single fare.

15 A further object of the invention is to provide a transfer of such nature that it may be used for passage from the issuing line to the destination, even where the passenger must travel on the cars of a number of intersecting lines.

20 A still further object of the invention is to provide a transfer ticket with means for indicating approximately the point at which a passenger boards the car.

25 A still further object of the invention is to provide a ticket with matter for indicating the month, day, hour and fraction of hour to which the use of the transfer is limited, this matter being so arranged as to permit convenient selection and punching by the conductor or other person.

30 With these and other objects in view, the invention consists in the novel construction and arrangement of parts hereinafter described, illustrated in the accompanying drawing and particularly pointed out in the appended claims, it being understood that changes in the form and proportions of parts may be made without departing from the invention.

40 The accompanying drawing illustrates a transfer ticket embodying the invention.

45 In the upper central portion of the ticket is a space 1 in which is printed the name of the company and matter stating the conditions under which the ticket may be used, and at the upper left hand corner is a space 2, bearing the name of the line by which the ticket is issued, the several intersecting or meeting roads on which the tickets are good

50 for passage each issuing a ticket bearing its own name and the tickets being preferably of distinctive color, so that they may be more readily identified by the conductor. In the ticket illustrated, this space 2 bears the words

55 "Transfer issued by the Punahoa Line." The printing on other tickets issued by the

remaining lines would be substantially the same, the name being changed.

In the lower left hand corner is a space 3 in which is printed the word "Special" and matter indicating the direction of travel, usually "North, South, East and West," this portion of the ticket being punched by the conductor when issued on special or emergency occasions.

65 At the right hand end of the ticket is a space 4 in which may be printed any suitable device for showing by punch marks the approximate time at which a car may be due at any transfer point. When the ticket is issued, the conductor should punch the hour and the minute mark nearest the time he is due at the junction where the passenger is to take another car and the conductor of the second car first ascertains whether the passenger wishes to be transferred to a third line or not. In the latter case, he takes up the ticket, but if a passenger is to be again transferred, the second conductor will punch the hour and minute nearest to the time at which 70 his car is due at the point where the passenger is to take the third car, and on the third car, and, if necessary, a fourth and fifth car, the same process may be repeated.

75 In the space 5, at the central portion of the ticket, is printed the names of the month and numerals from 1 to 31 for indicating the days of the month, this space being properly punched by the issuing conductor.

80 Below the space 5 and to the right of the "Special" space 3, is arranged a space 6, in which is printed matter indicating the zones through which the car travels from end to end of its route. Each zone may represent any part of the route of travel, but preferably the clearway between junction points, and each zone is distinguishably designated from the others by the names of the streets, roads, or land marks at opposite ends of said zones. Thus, for instance, the first zone is 85 indicated by the words "Paw.Je.--Man.Je.," these indicating a zone extending from Pawaa Junction to Manoa Junction, while the second zone is indicated by the words "Man. Je.--Alapai," these indicating Manoa 90 Junction at the beginning of the zone and Alapai street or crossing at the end of the zone. The entire route may be divided into as many zones as thought necessary and when a ticket is issued to a passenger, a 95 punch mark is made indicating the zone in which the passenger boarded the car, and if

an attempt is made by the passenger after completing a circuit of the road, to continue his ride without payment of another fare, the fact will be evident to the conductor.

5 In the space 7 below the month-and-day-indicating-space and to the right of the zone-indicating-spaces are arranged the names of all of the car lines, save the issuing line, on which the transfer is good for passage; with 10 suitable indicating marks employed to designate the direction of travel, such for instance as "N." "S." "E." & "W.", which the issuing conductor will punch opposite the name of the line to which the passenger is to 15 be transferred.

The charters of many street-railway companies compel the companies to carry passengers on any or on all intersecting or crossing lines which may be necessary for the passenger to use in traveling from one point to another, and in many instances the passenger is free to choose his own route, even though it be almost, if not entirely circuitous. This, under the usual form of transfer 20 tickets, compels the issuing of a transfer on a transfer, so that the identity of the payee of the fare is lost. Under the present system of issuing a transfer on a transfer, many passengers will continue riding for several hours 25 and in fact there is nothing in many of the systems as at present used to prevent the passenger from riding continuously for an unlimited period. It is often held, however, where franchises do not specifically enjoin 30 the practice, that a passenger is entitled to a ride including not more than one complete circuit by any route or combination of routes, and one of the principal objects of the present invention is to enable a car conductor to 35 readily ascertain when a passenger holding a transfer ticket has arrived within the zone in which he boarded the car on which his trip may have commenced. For instance, as the name of the issuing zone has been punched, 40 any attempt to pass beyond such zone or tendering a transfer originally issued in that

zone for fare, may be, by the use of this transfer ticket, circumvented, and another fare demanded, or the offender may be prosecuted for attempted fraud on the carrier. 50

The transfer ticket forms a complete and accurate record of the trip of the passenger from the time he boarded the first car, giving the zone of boarding, the name of the line issuing the ticket, the name of the second line and the time of transfer, and name of each subsequent line on which the ticket is used, each conductor punching the name of the line on which the ticket is to be next tendered for fare as well as the time his car is 55 due at the point of intersection with said line. 60

Having thus described my invention, what I claim and desire to secure by Letters Patent, is:—

A fare receipt for issuance to a passenger, 65 said fare receipt constituting a continuous transfer ticket arranged for the detection of circuit riders and having a group of spaces bearing names or symbols indicating transfer points at intersecting lines and being further provided with another group of spaces separate and independent of the transfer point symbols, each of such latter group of spaces bearing names or symbols indicating a zone through which the issuing car 70 travels, the names or symbols in each of the zone spaces indicating both the beginning and the end of a zone and the last name or symbol in each of these spaces being repeated as the first name in the next succeeding space, said zones covering the entire distance through which the issuing car travels 75 said tickets being arranged for transfer to intermediate or intersecting lines and back again to the issuing line. 80

In testimony whereof I affix my signature, in presence of two witnesses.

LEVI T. PECK.
